Primary Examiner — Austin Murphy(74) *Attorney, Agent, or Firm* — Kilpatrick Townsend & Stockton LLP(57) **CLAIM**

The ornamental design for a powered electric stylus as shown and described.

DESCRIPTION

FIG. 1 is a perspective view of a powered electric stylus showing our new design;

FIG. 2 is a second perspective view thereof;

FIG. 3 is a top plan view thereof;

FIG. 4 is a bottom plan view thereof;

FIG. 5 is a front elevation thereof;

FIG. 6 is a rear elevation view thereof;

FIG. 7 is a left side elevation view thereof; and,

FIG. 8 is a right side elevation view thereof.

The broken lines depict portions of the powered electric stylus in which the design is embodied that form no part of the claimed design.
